(57) **CLAIM**

The ornamental design for a housing of a controller for electronic game machine, as shown and described.

DESCRIPTION

FIG. 1 is a front, bottom and left perspective view of a housing of a controller for electronic game machine showing our new design, only the housing being represented by solid lines and others being represented by dotted lines;

FIG. 2 is a rear, top and right perspective view thereof;

FIG. 3 is a front view thereof;

FIG. 4 is a rear view thereof;

FIG. 5 is a right side view thereof, a left side view being a mirror image thereof;

FIG. 6 is a top plan view thereof; and,

FIG. 7 is a bottom plan view thereof.

The broken lines environmental are for illustrative purpose only and form no part of the claimed design.
